UNITED STATES PATENT OFFICE.

CHARLES KESSES, OF NEW YORK, N. Y.

PRINTING-MACHINE.

1,271,913.

Specification of Letters Patent. Patented July 9, 1918.

Application filed July 3, 1917. Serial No. 178,418.

To all whom it may concern:

Be it known that I, CHARLES KESSES, a citizen of the United States, residing at New York city, in the county and State of New 5 York, have invented a new and useful Printing-Machine, of which the following is a specification.

This invention is related to my application for a type and photo combination printing 10 machine, Patent 1,228,784, filed April 11, 1916, Serial No. 90,489, and that class of printing machines, wherein the impression is taken with a flat type-bed and the objects of my improvements are, first, to provide such 15 machines with an inking roller, which travels transversely in relation to the machine in a circle around said type-bed throughout the printing operation thereof; second, to regulate the machine for the size of successive 20 impressions in one or more colors required; third, to print with said flat type-bed on a constantly running paper in one or more colors; fourth, to print type impressions in one or more colors in one operation.

I attain these objects by the mechanism illustrated in the accompanying drawings in which—

Figure I is a front elevation of said printing 30 machine. Fig. II is a detail side view of the lower part of the printing carrier, showing the driving mechanism, for the ink fountain, ink curtain, ductor roller and the inking rollers. Fig. III is a detail of a top 35 view of said lower part of the printing carrier. Fig. IV is an eccentric wheel separated from its regulator. Fig. V is a sectional detail of said eccentric. Fig. VI is a roller shaft secured in a collar. Fig. VII is a 40 said collar in an open position. Fig. VIII is a regulator separated from its eccentric wheel. Fig. IX is a detail view of a ductor roller to feed ink from a curtain to a table while the inking rollers are running over the 45 type.

Similar characters refer to similar parts throughout the several parts.

A platform 1, is secured to legs or standards 2. A twin support 3 is secured to said 50 platform. A main carrier 4 is movable over the rollers 5, which are secured in said support. An eccentric wheel 6 set in a rotary rim, being shown in Fig. IV is operative between plane surfaces 7^a and 7^b to reciprocate said main carrier in said support. Said

eccentric must be a trifle smaller than the opening between said surfaces, to allow movement of said eccentric. A regulator 8 being shown in Fig. VIII is built in two parts A and B, part A is secured with a set 60 screw to a shaft 10, and screws 9 in said part secure said regulator in connection with part B in a suitable position to said eccentric. For instance, if the size of a print is 10 inches long, then said eccentric must be set, 65 to reciprocate said main carrier in said support 5 inches back and 5 inches forward, both movements combined must be 10 inches. Said eccentric is secured to a shaft 10, which is journaled with suitable bearings in 70 the front and the rear support 3. A gear 11 secured to said shaft is meshed to a gear 12 which is secured to a shaft 13 secured in duplex bearings in a support 14. Said support is secured in the rear of the machine to 75 the platform 1. The shaft 13 may be driven by a belt passing around the power wheel 15, to operate the different mechanical movements.

The lower part of said main carrier is a 80 printing platform 16, suitable guides 17 for paper 18 are slidably secured in a rail 19 in said platform to hold any width of paper while running over said platform in a good position.

A printing carrier 20 is reciprocated in a vertical direction on its rails in said main carrier by an eccentric 21, which is operative in an oblong frame 22, between plane surfaces. Said eccentric is secured to a shaft 90 23, which is journaled with suitable bearings in the front and the rear support 3. A gear 24 secured to said shaft is meshed to a gear 25 which is secured to an idle shaft 26 which is journaled in duplex bearings in the rear support 3, said gear being meshed to the gear 11. The oblong frame 22 is movable in a vertical direction on its guide rails in said printing carrier. Springs 27 are secured on said frame and a partition 100 of said carrier. A screw 28, which can be turned in the upper part of said carrier, is to lift or lower said carrier in the main carrier to an adjusted position, to give with said springs the correct pressure for the 105 printing required.

A type-bed 29 facing downward is secured in suitable rails in the lower part of the printing carrier. The side and a top view of said lower part being shown in 110

Figs. II and III. A suitable ink-table 30 facing upward is secured to the printing carrier.

Inking rollers 45 travel once for every 5 operation in a circle around said type bed and said inktable in the direction of the arrows, to ink the type when the printing carrier is at its highest position and to run over the inktable while the type is in printing contact, running at the same speed and in the same direction as the running paper.

The eccentric 21 must be regulated, to lift the printing carrier to a suitable height, to allow said inking-rollers to ink the type without 15 touching the paper, which is running constantly in transverse direction in relation to the inking rollers over the printing platform 16.

Means to transmit the motion causing 20 said inking rollers to travel is shown in Fig. II. A bevelgear 32 secured to the shaft 23 is meshed to a bevelgear 33, which is secured to a spiralgear 34. Said spiral gear is secured with suitable bearings underneath the rear support 3 and the platform 1, and is meshed to a pin-wheel 35, which is secured to a shaft 36^a journaled with suitable bearings in the rear extension on the printing carrier. Bevelgears 37 secured to 25 said shaft are meshed to bevelgears 38; said gears are secured to shafts 39, and bevelgears 40 secured to said shafts are meshed to bevelgears 41, which are secured to the shaft 42^a. Said shaft is journaled with 30 bearings in the printing carrier. The length of the pins in said pinwheel 35 must be $\frac{3}{4}$ of the length of the type-bed to allow movement of said pins in the spiral gear 34 for the size of prints required. The sprocket 35 wheels 43^a secured to the shaft 42^a are operatively connected with sprocket chains 44 to sprocket wheels 43^b, which are secured to shafts 42^b, which are journaled with duplex 40 bearings in the front part of the printing carrier.

The inking rollers 45 are secured with brackets 46 to the sprocket chains in a manner shown in Fig. VI. Said inking rollers are hollow, to be slid over shafts 47, screws 48 to secure said inking roller to said shafts. A collar 49 has screws to secure said shaft to said collar. An open position of said collar is shown in Fig. VII. The ends of said collar are journaled with bearings to 50 the brackets 46. All operative rollers in this machine must be secured in collars to be easily changed.

The pins 51 to secure said brackets to said sprocket chain must extend on one or 60 on both sides to run in a rail-support 52 as shown in Fig. III, to give to the inking rollers the correct pressure on the inktable and the type as required.

The ink is supplied to the inktable 30 by 65 an ink fountain roller 53 secured to shafts

54. An ink curtain 55 passes over two rollers, running constantly in one direction to supply the ink from the fountain to a ductor roller 56. Said ductor roller supplies the ink to the inktable as shown in Fig. IX. 70 The ductor-roller is secured to sleeves 57, which are slidable on the crank shafts 58, the springs 59 on said crank shafts giving correct pressure to the ductor roller when running in a plane over the inktable. 75

The motion to the fountain and to the ductor roller is given by bevelgears 60 which are secured to the shafts 42^b. Bevelgears 61 meshed to said gears are secured to shafts 62. Bevelgears 63 secured to said 80 shafts are meshed to bevelgears 64, which are secured to the crank-shafts.

Bevelgears 65 are meshed to the gears 64 and are secured to shafts 66. Bevelgears 67 secured to said shafts are meshed to bevelgears 68 which are secured to the driving 85 shaft of the fountain roller 53.

The motion to the ink-curtain is given by suitable pulleys secured to one of the ink-curtain rollers, connected with wire springs 90 with suitable pulleys secured to the crank-shaft.

By every operation of the machine the crank-shaft will rotate once to move the 95 ductor-roller over the inktable, when the inking rollers are running over the type, and will run over the ink-curtain when the inking rollers are running over the inktable.

A supply roll of paper is secured on the 100 hanger 69, said hanger is slidable in a rail 70 in the platform 1 and can be adjusted to hold any width of paper 18. Said paper is constantly drawn from the supply roll, through the guideways 17 over the printing platform 16 by a feeding device consisting of rollers 71 and 72. Roller 72 is secured to an idle shaft which hangs in springs 73 secured to the platform 1. Roller 71 can be easily changed for a larger or smaller roller. 110

If the size of print is 10 inches long, the circumference of said roller must be 10 inches. Said roller is secured with a set screw to a shaft 74, and a bevelgear 75 secured to said shaft is meshed to a bevelgear 76, which is secured to a shaft 77. A bevelgear 78 secured to said shaft is meshed to a bevelgear 79, which is secured to the driving shaft 13 of the machine. A second feeding device consisting of rollers 80 and 120 81 can be easily connected to the driving mechanism if required.

The ink-fountain, the ductor-roller, the inktable and the inking-rollers are built in parts slidable over shafts; as shown in Fig. III. When printing in one color secure said parts together with screws 48 to the shaft as shown in Fig. VI.

When printing in different colors, place washers 83 between said parts, and regu- 130

late the eccentric 6 for the size of one part. To regulate the machine for smaller sizes of prints in different color printing, it is necessary to use suitable smaller parts as shown 5 in dotted lines in Fig. III and the machine must be regulated for the size of those parts. The same size columns of type have to be inserted lengthwise in relation to the machine in the type-bed in a suitable position 10 to correspond with the inking rollers and print as usual.

The operation of the machine is as follows—

Place a roll of paper of the size required 15 in hanger-69, pass the paper through the guideways 17, place smoothly over the printing platform 16, between the rollers 71 and 72, and regulate the eccentric 6 for the size of print required.

20 Next, I show the coöperation of the several parts throughout a complete circle of movements involved in the printing. It will be seen that the type-bed remains parallel to a given plane throughout the printing 25 operation, and the range of its movements in the direction of this plane and at right angles thereto may be regulated as desired. When the power is applied the printing carrier is in the position shown in Fig. I, 30 showing the inking roller going to ink the type, and the ductor roller going to give ink to the ink-table. Then the main-carrier is moved by the eccentric 6 forward to the right and the printing carrier is moved upward by the eccentric 21. The inking roller running over the type and the ductor-roller gives ink to the inktable. The main carrier moves to its forward limit of movements and the printing carrier moves downwardly 35 to press the type against the constantly running paper lying on the top of the printing platform, while the inking rollers run over the inktable and the ductor roller up to the ink curtain. Then the carrier re- 40 turns to the position shown in Fig. I to be ready for the next operation.

I am aware that prior to my invention type printing machines have been made which printed in two or more colors with 50 rollers on constantly running webs or sheets, I therefore do not claim such machines but—

What I do claim as my invention and desire to secure by Letters Patent is—

1. In a printing machine for printing

constantly running paper, the combination 55 of a type-bed, of a mechanism to reciprocate said type-bed parallel with and at right angles to a given plane, an ink table in the rear of said bed, inking rollers, having means to traverse said form and said table 60 transversely in relation to the constantly running paper, a fountain, an ink curtain adjacent said fountain and a ductor roller for supplying ink from said curtain to said table. 65

2. In a printing machine, the combination of a type-bed, of a mechanism to reciprocate said type-bed parallel with and at right angles to a given plane, an ink table in the rear of said bed, inking rollers, sprocket 70 wheels, sprocket chains carrying said rollers and means for causing said rollers to traverse said bed and said table transversely in relation to the running paper, a fountain, an ink curtain adjacent said fountain, and 75 a ductor roller for supplying ink from said curtain to said table.

3. In a printing machine, the combination of a type-bed, of a mechanism to reciprocate said type-bed parallel with and at right angles to a given plane, an ink table in the rear of said bed, inking rollers, endless sprocket chains carrying said rollers, sprocket wheels, gear-wheels for rotating 80 said sprocket wheels, a spiral gear engaging 85 a pin wheel for driving said gear-wheels, whereby the ink-rollers are caused to run over the inktable, and the type-bed, an ink-curtain adjacent said fountain and a ductor roller for supplying the ink from said curtain to said table. 90

4. In a printing machine, the combination of a type-bed, of a mechanism to reciprocate said type-bed parallel with and at right angles to a given plane, an inktable in the 95 rear of said bed, inking rollers having means to traverse said type-bed and said ink-table, a fountain, a curtain adjacent said fountain, crank arms, a ductor roller slidably secured to crank arms, springs on said arms for 100 causing said ductor roller to supply the ink from the ink curtain and to move in a plane over said ink-table.

CHARLES KESSES.
